W. R. POTTS

PRESS FOR TENNIS AND OTHER RACKETS

Filed Feb. 11, 1925

Inventor
W. R. POTTS

by J. A. Justice 1774.

UNITED STATES PATENT OFFICE.

WILLIAM REYNOLDS POTTS, OF LONDON, ENGLAND.

PRESS FOR TENNIS AND OTHER RACKETS.

Application filed February 11, 1925. Serial No. 8,489.

To all whom it may concern:

Be it known that I, WILLIAM REYNOLDS POTTS, a subject of the King of England, residing at 210 Philip Lane, Tottenham, 5 London, N. 15, Kingdom of England, have invented certain new and useful Improvements in or Relating to Presses for Tennis and Other Rackets, of which the following is a specification.

10 This invention relates to presses for tennis and other rackets, the chief object being to provide for such presses being attached and detached in a more simple, efficient and expeditious manner than heretofore.

According to this invention, the improved press comprises a frame having associated therewith spaced members adapted to retain a racket detachably in position with respect to the said frame. The said spaced members may be angularly movable and adapted to engage the racket. The invention also contemplates a press comprising a frame, spaced upright elements secured to the said frame, members movable angularly and longitudinally relatively to the said elements and having lateral extensions or the like, and means associated with the said elements adapted to co-operate with the said 25 elements and with the said members to cause the said extensions to engage a racket and detachably retain the same in position with respect to the said frame. The spaced upright elements may be screw-threaded and engaged by nuts adapted to co-operate with the members which are movable longitudinally and angularly relatively to the said elements. The said lateral extensions may be padded at the engaging faces 30 thereof.

In order that the said invention may be clearly understood and readily carried into effect the same will now be described more fully, by way of example, with reference 45 to the accompanying drawing, in which:—

Figure 1 is an end elevation of a tennis racket press embodying the invention,

Figure 2 is a top plan view thereof.

Figure 3 is a perspective view showing 50 the press applied to a tennis racket, and

Figure 4 is a fragmentary detail sectional view, on an enlarged scale, showing part of the means for securing the press to the racket.

55 Referring to the drawing, the press comprises a frame *a* of open formation and of

the configuration shown more particularly in Figure 2, but it will be understood that the frame may be of rectangular or other suitable shape and may be made of metal, such as aluminium or the like, or may be made of wood or other suitable material or materials, according to requirements. The said frame is provided with spaced upright elements *b*, which may be in the form of screw-threaded bolts, pins or the like secured thereto, the said elements being shown as arranged in pairs at opposite sides of the frame. The said elements have associated therewith members *c* comprising bosses or sleeves *d* (see more particularly Figure 4) freely surrounding the upright elements *b*, so as to be capable of moving angularly relatively thereto, and provided with lateral extensions *e*, adapted to extend, when desired, inwardly above the upper face of a racket *f* at the sides thereof, when the racket is disposed on the frame, as shown in Figure 3, whereby the said extensions *e* may be caused to engage the racket and clamp the same to the frame. This clamping action may be effected by means of nuts *g* in threaded engagement with the said upright elements causing the said members to move downwardly with respect to the upright elements *b*, thereby enabling the lateral extensions *e*, when directed downwardly, to engage with the upper face of the racket and effectively secure or clamp the racket to the frame *a*. The nuts shown are of the winged type, but nuts of the ordinary form, or nuts provided with handles, may be employed, if desired. The extensions *e*, in the example shown, are each provided with a pad *h* of felt or other material at the lower face thereof to engage with the racket, see more particularly Figure 4, whilst the upper face is inclined longitudinally.

It will be understood that when the press is to be detached from the racket, the nuts *g* are rotated so as to move outwardly relatively to the upright screw-threaded elements *b* to relieve the pressure on the members *c*, thereby permitting the said members to be moved angularly relatively to the said elements *b* in such a manner that the extensions *e* are moved outwardly clear of the racket, whereupon the press can be detached from the racket.

If desired, springs may be interposed between the members *c* and the frame *a*, in which case the said members may be recessed

at the lower faces of the bosses *d* thereof to receive partially the said springs. Further, the said members *c* may be so adapted as to move in unison in pairs, at each side of the frame, into operative and inoperative positions.

What I claim is:—

1. A press for tennis and other rackets, comprising a frame, spaced uprights secured to said frame, members movable angularly and longitudinally relative to the uprights and having lateral extensions, and means to

adjustably secure said members on the uprights.

2. A press for tennis and other rackets, comprising a frame, threaded uprights projecting therefrom, members loosely engaging the uprights and having lateral extensions, and elements screwed upon said uprights to cooperate and bind the members. 20

In testimony whereof I have hereunto signed my name.

WILLIAM REYNOLDS POTTS.
